Patented Dec. 27, 1921.

UNITED STATES PATENT OFFICE.

JOSEPH H. FLETCHER, OF LOS ANGELES, CALIFORNIA, ASSIGNOR TO PERFECTION
AUTO WINDOW COMPANY, OF LOS ANGELES, CALIFORNIA, A CORPORATION OF
ARIZONA.

WINDOW FOR FABRIC WALLS.

1,401,528.

Specification of Letters Patent. Patented Dec. 27, 1921.

Application filed January 4, 1918. Serial No. 210,272.

To all whom it may concern:

Be it known that I, JOSEPH H. FLETCHER, a citizen of the United States, residing at Los Angeles, in the county of Los Angeles 5 and State of California, have invented a new and useful Window for Fabric Walls, of which the following is a specification.

This invention pertains to windows of a type suitable for installation in automobiles, 10 tents and the like.

An object of the invention is to provide a window which is easy to install, in fact one so easily installed that the owner of the tent or automobile can install it himself 15 since very little mechanical knowledge and no special tools are required.

Another object is to provide a construction which is absolutely water-tight.

Another object is to aid in supporting the 20 window by suitable ribs so as to avoid sagging of the fabric wall.

Other objects and advantages will appear in the subjoined detail description.

The accompanying drawings illustrate the 25 invention:

Figure 1 is a front elevation of the invention, only portions of the fabric wall being shown.

Fig. 2 is an inverted plan section on line 30 indicated by x^2-x^2 , Fig. 1.

Figs. 3 and 4 are elevations respectively of the two frame members, looking at the opposing faces thereof.

Fig. 5 is an enlarged sectional detail on 35 line indicated by x^5-x^5 , Fig. 1.

The fabric walls 1 may be constructed of any suitable material such as employed in the manufacture of automobile tops, tents and other flexible walled structures. There 40 are provided frame members 2, 3 of any desired shape adapted to be placed on opposite sides of the wall 1 so as to embrace the wall therebetween, said members being in this instance in the form of rings and the member 2 being provided with a flange or tongue 45

4 which seats in a groove 5 in the frame member 3. With the exception of the tongue 4 and groove 5 the opposing faces of the frame members 2, 3 are flat inside and outside of the tongue and groove as at *a* and *b* so that when they are clamped on opposite sides of the fabric by means of screws 6 the fabric wall will extend from the outer to the inner edge of the frame member and 50 will lie flat against the flat portion of the

inner face of the frame member 2, as clearly shown in Figs. 2 and 5. Portions of the fabric wall will be crimped into the groove 5 by the action of the tongue 4, as clearly shown in Fig. 2. The screws 6 are inserted 60 through holes 7 in the frame member 3 and are screw-threaded into holes 8 in the frame member 2. This makes a neatly constructed window frame especially if the screws be countersunk as shown. 65

The flat portions of *a*, *b* taken together are relatively wide so that there are comparatively large contacting areas between the fabric wall 1 and the frame members 2, 3 thus to insure against leakage of moisture 70 through the joint between said members.

The member 2 is provided around its inner edge with an annular recess 9 in which is adapted to seat the marginal portion of a transparent pane 10. The pane 10 may 75 be formed of beveled plate glass, but it is understood that it may be constructed of any suitable transparent or semi-transparent material suitable for transmitting light. By referring to Figs. 2 and 5, it is seen that the 80 marginal portion of one face of the pane 10 seats directly against the portion of the fabric wall 1 adjacent the recess 9 so that the portion of the fabric wall engaging the pane functions as a gasket. Thus it is clear 85 the fabric wall 1 packs the joint between the frame members 2, 3 and also packs the joint between the frame member 3 and pane 10 so as to insure against the passage of moisture through the window. The tongue 4 and groove 5 constitute interfitting means 90 that, though shown in the drawings as being continuous, need not necessarily be so, since the advantage last above mentioned will result even though the interfitting means 95 take the form of spaced projections and recesses therefor.

If the pane 10 be made of glass, especially of heavy plate glass, there is a tendency for the upper portion of the fabric wall to sag 100 under the weight of the glass and frame members, and to prevent this the following construction is provided: Ribs 11 in any desired number are provided, the ends of said ribs adjacent the frame members being accommodated in channels 12 extending transversely of the inner face of the frame member 3. These ribs 11 may be formed of box plaits made of the fabric itself, or may be formed of metal strips or, as in the instance 110

shown in the drawings, may be formed by combining the box plaits and strips, said strips being inserted in the box plaits. When the metal strips are employed they add stiffness to the fabric wall and they so support the frames and pane as to take the strain off of the fabric wall.

In practice, to install the invention, the frame members 2, 3 will be placed on opposite sides of the fabric wall 1 prior to cutting the window opening therein with the pane 10 seated in the frame member 2 and the screws 6 will be inserted in the holes 7 and through perforations previously made 15 in the fabric and will be turned up tight in the holes 8 to firmly clamp the fabric between the flat opposing faces and tongue and groove of the members 2, 3 and between the marginal portion of the pane 10 and 20 the flat face of the member 3, as clearly shown in Fig. 2. When this is done the fabric 1 will have a portion 13 extending along one face of the pane 10 within the space defined by the inner edge of the frame member 3, as clearly shown in Fig. 2. Then 25 the person installing the device will cut out the portion 13 with a sharp knife, the inner edge of the frame member 3 functioning to accurately guide the knife blade so that the 30 fabric will be cut clean to the inner edge of the frame member to form a window opening 14 in the fabric as in Figs. 1 and 5.

I claim:

1. A window comprising two rigid frame members adapted to be placed on opposite sides of a fabric wall, said frame members having relatively wide opposing flat face portions and having a tongue and a groove respectively interfitting one another, one of 35 said frame members having an annular recess in its inner margin adjacent the flat face of the other frame member, a pane having its marginal portion seated in the recess, and means to hold the frame members 40 toward one another to simultaneously clamp said marginal portion of the pane and the fabric wall therebetween.

2. The combination with a fabric wall having an opening therein, of frame members on opposite sides of the fabric wall, said frame members having relatively wide opposing flat portions and having an annular groove respectively interfitting one another and one of said frame members having 45 an annular recess adjacent the flat face of the other frame member, a pane having its marginal portion seated in the recess, the

fabric wall extending between one side of the pane and the flat face of the last named frame member and between the tongue and groove, and means to hold the frame members toward one another to simultaneously clamp the marginal portion of the pane and the fabric wall therebetween.

3. The combination with a flexible fabric 65 having an opening therein, of a window for said opening comprising a frame secured to the margin of the fabric surrounding said opening, a glass for said frame, and means to support said window independently of 70 said fabric.

4. In a vehicle top, the combination with flexible cover means therefor having an opening therein, of a glass in said opening, and means to support the glass independently of the flexible cover means.

5. The combination with a fabric wall having an opening therein, of frame members on opposite sides of the fabric wall, said frame members having relatively wide 80 opposing flat clamping portions provided with interfitting curtain gripping means and one of said frame members having a recess adjacent the flat face of the other frame member, a pane having its marginal portion 85 seated in the recess, a fabric wall extending between the interfitting means, and means to hold the frame members toward one another to simultaneously clamp the marginal portion of the pane and the fabric wall therebetween.

6. The combination with a fabric wall having an opening therein, of frame members on opposite sides of the fabric wall, said frame members having relatively wide 95 opposing flat clamping portions provided with interfitting tongue and groove curtain gripping means and one of said frame members having a continuous recess adjacent the flat face of the other frame member, 100 a pane having its marginal portion seated in the recess, the fabric wall extending between the tongue and groove, and means to hold the frame members toward one another to simultaneously clamp the marginal portion of the pane and the fabric wall therebetween.

Signed at Los Angeles, California, this 20 day of December, 1917.

JOSEPH H. FLETCHER.
